UNITED STATES PATENT OFFICE.

FRANKLIN A. REECE, OF BROOKLINE, MASSACHUSETTS, ASSIGNOR TO THE REECE
BUTTON HOLE MACHINE COMPANY, OF BOSTON, MASSACHUSETTS, A CORPORA-
TION OF MAINE.

STOP MOTION FOR SEWING MACHINES AND THE LIKE.

Application filed March 13, 1925. Serial No. 15,412.

This invention relates to stop motions for sewing machines and the like and particularly to a stop motion of the type illustrated in United States Patents No. 367,063, July 5 23, 1887, and No. 713,764, November 18th, 1902. These patents show a driving and stopping mechanism which comprises a driving pulley having a shoulder and mounted

- 10 on a shaft, a clutch dog pivotally mounted on a hub fast to the shaft and adapted to engage the shoulder of the pulley, said dog being urged toward this operative position by a spring, and a clutch-disengaging member which is normally latched in its inoperative 15 position but which when released is moved into its operative position to engage the tail of the dog and thereby swing the latter about its pivot and release it from the shoulder of the driving pulley, said clutch-disengaging member co-operating with the dog after it has been released to bring the shaft to rest.

The machine shown in said patents is a buttonhole sewing machine which includes a 20 stitch-forming mechanism and work-holding means having a movement relative to each other and in said machine the latch is released at the proper time in the cycle of movements by such relative movement.

- 25 30 In actual practice it sometimes happens that this release of the latch occurs just as the tail of the clutch dog is passing the clutch-disengaging member and when this condition obtains there is the possibility that said clutch dog will wipe by the clutch-disengaging member thus causing the latter to rebound or causing what is termed a "fly over."

It is one of the objects of my present invention to provide an improvement in this 40 type of stop motion which will eliminate any possibility of such a rebound or "fly over" and which will invariably ensure the proper stopping of the shaft when the machine is released.

The features wherein the invention resides will be pointed out in connection with the following description of a selected embodiment of my invention.

- 45 50 Fig. 1 is a side view of a buttonhole sewing machine having my improvements ap-

plied thereto, said section being taken on substantially the line 1—1, Fig. 2;

Fig. 2 is a fragmentary top plan view of the driving and stopping mechanism; 55

Figs. 3 and 4 are fragmentary sectional views taken on substantially the line 3—3, Fig. 2 but illustrating different positions of the parts.

Fig. 5 is a fragmentary sectional view 60 illustrating different positions of the clutch-disengaging member.

As intimated above the present invention is shown as it might be applied to a button-hole sewing machine of the type illustrated 65 in the above-mentioned Patent No. 713,764. Said sewing machine is provided with a bed plate 1 carrying work-holding means in the form of work clamps 2. It is also provided with the usual stitch-forming mechanism 70 which includes a needle 3 operative above the work and also includes an under thread-handling mechanism operating beneath the work but which is not herein shown, said 75 stitch-forming mechanism being mounted on a head 4 that is herein shown as movable back and forth upon the bed plate 1, this movement providing the necessary relative movement between the stitch-forming mechanism and work-holding means to accomplish 80 the stitching along the edges of the button-hole.

The stitch-forming mechanism is operated from a driving shaft 5, all as usual in machines of this sort and this shaft is in turn 85 driven from a driving pulley 6 which is loosely mounted on the shaft.

The clutch herein shown for clutching the pulley to the shaft is similar to that illustrated in the above-mentioned patent. It 90 comprises a clutch dog 7 pivotally mounted at 8 on a hub 9 which is fast on the shaft 5, said dog having a nose 10 adapted to engage a shoulder 11 formed on the pulley. The dog is acted upon by a spring 12 which tends to throw it into its operative position with its nose in engagement with the shoulder 11 and when the parts are thus engaged the clutch is operative and the shaft 5 will be driven from the driving pulley 6. The 100 clutch is released at proper times by means of a clutch-disengaging member 13 which is

adapted to engage the tail 14 of the clutch dog, the engagement of said tail with the clutch-disengaging member swinging the dog about its pivot 8 and thereby withdrawing the nose 10 from the shoulder 11.

This clutch-disengaging member 13 is carried by a rocking member 15 fast on the shaft 16 and said shaft has fast thereto an arm 17 which is acted on by a spring 18, said spring tending to move the clutch-disengaging member forwardly into its operative position. The clutch-disengaging member is retained in its inoperative position while the clutch is in engagement by means

of a latch member 19 pivoted at 20 to the head 4 and having a shoulder 21 adapted to engage a projection 22 on the arm 17.

So long as the latch engages the projection 22 as shown in full lines Fig. 3 the clutch-disengaging member is retained in its inoperative position out of the path of movement of the tail 14 of the clutch dog as shown in Fig. 5, (said path being shown by the dotted circular line 41 in Fig. 5), and the clutch will, therefore, remain operative. When, however, the latch 19 is released from the projection 22 then the spring 18 tends to swing the clutch-disengaging member 13 forwardly into its operative position, in which it is in the path of movement of the tail 14 of the dog 7.

The clutch-disengaging member is provided with an arm 23 having a roll 24 at its end and the hub 9 is formed with a cam surface 25 situated in line with the roll 24. This cam surface has a high concentric portion 26 and a low portion 27. The high portion 26 has such radial dimensions that when the roll 24 rests against it as shown, in Fig. 4, the clutch-disengaging member 13 will be held just out of the path of movement of the tail 14 of the dog, as shown by its intermediate position in Fig. 5. When, however, the low portion 27 comes under the roll 24 then the clutch-disengaging member is moved forward into its operative position by the spring 18 and is brought into the path of movement of the tail 14 of the dog as shown by the left hand dotted line 50 position Fig. 5.

The latch 19 is released from the lug 22 by the movement of the head 4, all as shown in the above-mentioned patent, and for this purpose the bed frame is provided with a rib or abutment 28 which is adapted to engage a screw 29 carried by the lower end of the latch 19 as the head 4 moves forward, it being understood that the latch is pivotally mounted on the head and moves therewith.

The parts are so adjusted that the screw 29 will engage the abutment 28 just before the stitching is completed on the buttonhole and the feeding movement which takes place 65 during the formation of the last few stitches

will gradually swing the latch 19 from the full to the dotted line position Fig. 3 and thereby release it. The final release of the latch, however, may take place when the shaft 5 and the clutch dog is in any angular 70 position. If the release takes place when the shaft and clutch dog are in the position shown in either Fig. 3 or 4 then the first movement of the clutch-releasing member due to the action of the spring 18 will bring 75 the roll 24 against the high concentric portion 26 of the cam 25 and as the cam turns and the low portion 27 passes under the roll 24 the clutch-releasing member will have a further inward movement bringing it into 80 the path of the tail 14 so that the dog will be released and the shaft 5 brought to rest.

It sometimes happens, however, that the final release of the latch will occur when the low portion 27 of the cam has partially 85 passed the roll 24 and when the tail 14 of the dog is just about opposite the clutch-releasing member 13. If the release occurs at this time the clutch-releasing member, when it moves forward, is apt to strike the 90 end of the tail of the dog and if this occurs the clutch may not be released and the impact is likely to cause the clutch-releasing member to rebound, thus allowing what is termed a "fly over."

It is one of the objects of my present invention to provide a novel device for preventing this from happening and I accomplish this by providing an abutment or stop which functions temporarily to arrest the 100 clutch-releasing member when the latch is released and which holds it arrested during a partial rotation of the shaft and until the dog has just passed the clutch-releasing member and then to allow the clutch-releasing member to move forwardly into a position controlled by the high portion 26 of the cam 25 as shown in Fig. 4. This abutment or stop member is shown as a lever 30 pivoted at 31 to an arm or bracket 32 which is secured to the head 4, said lever being acted on by a spring 33 which tends to move it downwardly. This lever 30 carries a roll 34 which operates on a cam surface 35 formed on the hub 9. The cam surface 35 has the low portion 36 extending throughout the greater portion of its periphery and the relatively short high portion 37. As the cam rotates, therefore, the lever 30 has an up and down movement, it being moved upwardly by the high portion of the cam and moved downwardly by the spring 33, the latter keeping the roll in engagement with the cam.

The arm 15 of the clutch-releasing member is provided with an extension 38 which is in line with the end of the arm 30 when the latter is in its lowered position. The arm 30 is such a length that when the clutch-disengaging member is latched in its inoperative 120

position, as shown in full lines, Fig. 3, the end 39 of said arm is slightly separated from the extension 38 as shown in Fig. 3. This is the position which the parts assume while the machine is operating and during the operation the arm 30 will have an up and down movement, as indicated by the full and dotted lines in Fig. 3.

When the latch 19 is released, as shown in dotted lines, Fig. 3, the clutch-disengaging member will move slightly forward under the influence of the spring 18 thus bringing the extension 38 into engagement with the end of the arm 39. When the parts are in this position the clutch-disengaging member is still outside the path of movement of the tail 14 of the dog 7. This release of the latch 19 may occur when the shaft 5 is in any angular position and assuming that it occurs when the shaft is in approximately the position shown in Fig. 3 then it will be understood that the clutch-disengaging member will be moved forward by the spring 18 until the extension 38 engages the end 39 of the stop arm 30. The clutch-disengaging member will be held in this position by the stop arm 30 while the shaft continues its rotation and until the high part 37 of the cam surface 35 passes under the roll 34, as shown in Fig. 4. When this happens then the arm 30 is lifted above the extension 38 and the clutch-disengaging member is again released. It will then move forward under the influence of the spring 18 to bring the roll 24 against the cam surface 25 as seen in Fig. 4 and in this position the extension 38 is beneath the end 39 of the stop arm 30 so that when the stop arm moves downwardly again it will rest on the top of the extension 38. When thereafter the low portion 27 of the cam 25 passes under the roll 24 then the clutch-disengaging member is permitted to move forwardly into operative position to disengage the clutch.

The cams 35 and 25 are rigid with each other and have such a relative position that the high portion 37 of the cam 35 will always operate to raise the stop arm 30 just after the low portion 27 of the cam 25 has passed by the roll 24, as shown in Fig. 4. Hence the clutch-disengaging member is always released from the arm 30 at a predetermined point in the rotation of the shaft 5 so that when the clutch-disengaging member moves forward after its release from the arm 30 the roll 24 will always engage the cam 25 at approximately the same point.

The parts are preferably so timed that the release of the clutch-disengaging member from the arm 30 will take place just after the low portion 27 of the cam 25 has passed the roll 24 so that the shaft 6 will have about one-half or three-quarters of a revolution to make between the time that the clutch-disengaging member is released from the stop

arm 30 and the time when the low portion 27 of the cam comes under the roll 24. The arm 30, therefore, and its co-operating cam 35 brings the final movement of the clutch-disengaging member into absolute timed relation with the rotation of the shaft 6 and this precludes the possibility of the "fly over" as above described.

I claim:

1. In a sewing machine having stitch-forming mechanism and work-holding means movable relative to each other, the combination with said stitch-forming mechanism and work-holding means, of a clutch for operating the stitch-forming mechanism, a clutch-disengaging member, a latch to hold the clutch-disengaging member in inoperative position, means to release the latch by the relative movement between the stitch-forming mechanism and work-holding means, and two devices, both operating in timed relation with said clutch but acting successively to control the movements of the clutch-disengaging member into its operative position after it is unlatched.

2. In a sewing machine having stitch-forming mechanism and work-holding means movable relative to each other, the combination with said stitch-forming mechanism and work-holding means, of a driving shaft for operating the stitch-forming mechanism, a clutch by which the shaft is driven, a clutch-disengaging member, a latch to hold the clutch-disengaging member in its inoperative position, means to release the latch by the relative movement between the stitch-forming mechanism and work-holding means, a spring tending to move the clutch-disengaging member into its operative position, a stop arm mounted separately from the clutch-disengaging member and operative in one position to engage said member and restrain the spring-impelled movement thereof, said stop arm being capable of movement relative to said clutch-disengaging member, and means operative when said shaft is in a predetermined angular position to move said stop arm into inoperative position in which it is out of engagement with the clutch-disengaging member.

3. In a sewing machine having stitch-forming mechanism and work-holding means movable relative to each other, the combination with said stitch-forming mechanism and work-holding means, of a driving shaft for operating the stitch-forming mechanism, a clutch by which the shaft is driven, a clutch-disengaging member, a latch to hold the clutch-disengaging member in its inoperative position, means to release the latch by the relative movement between the stitch-forming mechanism and work-holding means, a spring tending to move the clutch-disengaging member into its operative position, a stop arm pivotally mounted

independent of the clutch-disengaging member, said stop arm when in operative position restraining the spring-impelled movement of the clutch-disengaging member, and a cam on the shaft for moving said stop arm into inoperative position.

4. In a device of the class described, the combination with a shaft to be driven, of a clutch for driving the shaft, a spring-actuated clutch-disengaging member, a latch to hold said member inoperative, means operating in non-timed relation to the rotation of the shaft to release the latch, whereby the angular position of the shaft at the time of the release of the latch is indeterminate, a stop member movable relative to the clutch-disengaging member and adapted to engage the latter after it has been released and maintain it in its inoperative position, and means rotating in timed relation with the shaft and acting on the stop member to move it into a position to free the clutch-disengaging member when the shaft occupies a predetermined angular position.

5. In a device of the class described, the combination with a shaft to be driven, of a clutch for driving the shaft, a spring-actuated clutch-disengaging member, a latch to hold said member inoperative, means operating in non-timed relation to the rotation of the shaft to release the latch, whereby the angular position of the shaft at the time of the release of the latch is indeterminate, a vibrating stop member movable in timed relation to said shaft into and out of operative position, said stop member when in operative position maintaining the clutch-disengaging member inoperative, and when in inoperative position releasing the clutch-disengaging member.

6. In a sewing machine having stitch-forming mechanism and work-holding means movable relative to each other, the combination with said stitch-forming mechanism and work-holding means, of a shaft for operating the stitch-forming mechanism, a clutch for driving the shaft, a spring-actuated clutch-disengaging member, a latch

to hold said member in inoperative position, means to disengage the latch by the relative movement between the stitch-forming mechanism and the work-holding means, a cam on said shaft for controlling the final movement of the clutch-disengaging member into its operative position, and means controlled by said shaft to effect the engagement of the clutch-disengaging member with the cam when the shaft is in a predetermined angular position.

7. In a sewing machine, the combination with stitch-forming mechanism and work-holding means movable relative to each other, of a shaft for operating the stitch-forming mechanism, a clutch for driving the shaft, a spring-actuated clutch-disengaging member, a latch to hold said member inoperative, means to release the latch by the relative movement between the stitch-forming mechanism and work-holding means, and two successively acting devices, both operating in timed relation with said shaft to control the spring-actuated movement of the clutch-disengaging member into its operative position so that said movement is effected in two stages.

8. In a sewing machine, the combination with stitch-forming mechanism and work-holding means movable relative to each other, of a shaft for operating the stitch-forming mechanism, a clutch for driving the shaft, a spring-actuated clutch-disengaging member, a latch to hold said member inoperative, means to release the latch by the relative movement between the stitch-forming mechanism and work-holding means and two successively-acting devices, one of which is mounted independently of the clutch-disengaging member and both of which operate in timed relation with the rotation of the shaft to control the spring-actuated movement of the clutch-disengaging member into its operative position so that said movement is effected in two stages.

In testimony whereof, I have signed my name to this specification.

FRANKLIN A. REECE.
